UNITED STATES PATENT OFFICE.

HERBERT E. BARRON, OF DUPO, ILLINOIS.

PASTE-TUBE COLLAPSER.

Application filed May 19, 1923. Serial No. 640,039.

To all whom it may concern.:

Be it known that I, HERBERT E. BARRON, a citizen of the United States, residing at Dupo, in the county of St. Clair and State 5 of Illinois, have invented certain new and useful Improvements in Paste-Tube Collapsers, of which the following is a specification.

In carrying out the present invention, it 10 is my purpose to provide a device that is adapted for the reception of a tube of paste, and that is provided with means for collapsing the tube, whereby the material is fully and expeditiously ejected therefrom.

15 A primary object of the invention resides in the provision of such a device that is comparatively simple of construction, and one that may be easily operated, the device comprising relatively few parts correlated 20 in such a manner as to reduce the possibility of disarrangement to a minimum.

25 The nature and advantages of the invention will be better understood when the following detailed description is read in connection with the accompanying drawings, the invention residing in the construction, combination, and arrangement of parts as claimed.

30 In the drawings forming part of this application, like numerals of reference indicate similar parts in the several views, and wherein:

35 Figures 1 and 2 are elevations of opposite sides of my device.

Figure 3 is an end view thereof.

Figure 4 is a longitudinal cross section upon the line 4—4 of Figure 3, and looking in the direction of the arrows.

Figure 5 is a detail transverse cross section upon the line 5—5 of Figure 1.

Figure 6 is a fragmentary perspective of the carriage for the tube collapsing rollers and

40 Figure 7 is a perspective of a roller tension and spring employed in conjunction with the invention.

45 My novel tube collapser comprises a relatively elongated container 5 of suitable dimensions that is equipped with a hinged lid 6, that is adapted to be maintained in a locked position, through the medium of swinging hooks 7, that are pivoted to the container and adapted for engagement over pins 8 upon said lid 6. The front end of

the container 5 is formed with a vertical slot 9, the upper end of which terminates at the upper edge of said end wall, one side wall of said container being formed with a longitudinally extending slot 10, that is preferably adjacent the upper edge of this side wall, as more clearly shown in Figures 1 and 5.

Within the container 5 is a carriage designated generally 11, the same comprising end plates 12 and 13 that preferably have close contact with the end walls of said container, and are maintained in operated positions by bars 14 at opposite sides of the plate and adjacent the lower edge thereof. Immediately above the bars 14 are other 70 bars 15, the top sides of which are formed with rack teeth 16 for purposes hereinafter described.

Slidable upon the carriage 11 is a cross plate 17, the opposite ends of which are 75 formed with longitudinal bars for receiving the pair of bars 14 between the end plates 12 and 13 comprised in the carriage 11. This plate 17 is provided adjacent its opposite ends with vertically directed legs 18, each of which is formed with a vertical slot 19. Freely vertically movable within the slots 19—19 of the legs 18—18 are the opposite ends of an upper and lower shaft 20 and 21, each of which carries between the 85 legs a roller 20' and 21', respectively.

The opposite ends of the shaft 20 are provided with spur gears 22 that are in mesh with the teeth 16 of the bars 15. These gears 22 are relatively wide, and mesh 90 with narrower gears 23 upon the opposite ends of the lowermost roller shaft 21. The roller 21' is normally maintained in close engagement with the roller 20', through the medium of a curved spring 24, that has contact at its central portion with the before mentioned plate 17, and is bent upwardly at its opposite ends to provide fingers 25 that are notched for engagement 95 with the opposite ends of the roller shaft 21. One end of the top roller shaft 20 is formed with a squared extension 26, that projects through the said slot 10 in the side wall of the container 5, which carries a key 26'.

The front plate 13 of said carriage 11 is 100 provided with a slot 13' that registers with the opening 9 in the front wall of the container for permitting of the usual screw

threaded neck of a collapsible paste tube to project therethrough, when the same is positioned within the container as per Figure 4.

This end of the container 5 is equipped 5 with a pivot latch plate 27 that is adapted to be swung over the said screw threaded neck of the paste tube for maintaining the same in proper position.

In view of the above description, it will 10 at once be apparent that when a paste tube A is positioned within the container as shown in Figure 4, the tube may be collapsed for consequently discharging the paste therefrom by imparting a turning movement to the key 26', which will consequently cause a rotation of the rollers 20' and 21' in opposite directions, the movement of these rollers forwardly in the direction of the arrow of the figure will cause a collapsing 15 of the tube, it being of course understood that in this connection, the end of the tube must be inserted between said rollers.

Numerous advantages of a device of this 20 character will be readily appreciated by those skilled in the art, and even though I have herein set forth the most practical embodiment of the invention with which I am now familiar, it is nevertheless to be understood that minor changes may be made 25 in the invention without departing from the spirit and scope of the appended claims.

Having thus described my invention, what

I claim as new, and desire to secure by Letters-Patent, is:

1. A paste tube collapser including a casing, a frame removably mounted in said casing having end plates connected at the side portion of said casing by guide bars and rack bars, a tube collapsing member slidably mounted on said guide bars having slotted uprights extending therefrom, a pair of rollers mounted in said slotted uprights having intermeshing gears at the opposite ends thereof, the gears of one roller meshing with the racks carried by said frame, and means carried by the tube collapsing member for normally holding said rollers in contact, and operating means for said rollers, whereby a paste tube will be collapsed by the rollers in the rotation thereof during 40 the sliding movement on said guide bars.

2. A paste tube collapser including a casing for receiving a paste tube, a frame removably mounted in said casing having end plates connected by guide bars and rack 55 bars, a paste tube collapsing member slidably mounted on said guide bars having means carried thereby for engaging the rack bars for sliding said member on said guide bars adapted to engage and collapse a paste 60 tube in the movement thereof.

In testimony whereof I affix my signature.

HERBERT E. BARRON.
